UNITED STATES PATENT OFFICE.

FRANK FOWLER AND AMOS M. ULMER, OF PHILADELPHIA, PENNSYLVANIA.

SASH-FASTENER.

SPECIFICATION forming part of Letters Patent No. 423,751, dated March 18, 1890.

Application filed September 2, 1889. Serial No. 322,659. (No model.)

To all whom it may concern:

Be it known that we, FRANK FOWLER and AMOS M. ULMER, both citizens of the United States, and residents of Philadelphia, Pennsylvania, have invented certain Improvements in Sash-Retaining Devices, of which the following is a specification.

The object of our invention is to provide means whereby a window-sash or both of the sashes may be readily locked in the closed position or may be securely held in different partly-opened positions. This object we attain in the manner hereinafter set forth, reference being had to the accompanying drawings, in which—

Figure 1 is a view of the lower portion of a window frame and sash constructed in accordance with our invention, one of the side rails of the window-frame being removed and certain covering-plates on the sash being detached in order to show the bolt-operating mechanism carried by said sash. Fig. 2 is a section on the line 1 2, Fig. 1, showing in elevation the bolt-operating mechanism at the side of the sash. Figs. 3 and 4 are perspective views of said bolt-operating mechanism, showing it in two different positions. Fig. 5 is a sectional plan view of the mechanism for effecting the locking of the two sashes together. Fig. 6 is a vertical section of the same.

A represents part of the fixed frame of a window, a one of the side rails of the same, and B the sash, guided in the frame, as usual.

Each of the side rails a of the window-frame has adjacent to one face of the sash a recessed bar or plate b, as shown in Fig. 2, and the sash has at each side a casing d, within which is pivoted a bolt f, the latter having slots g g' located one above the pivot and one below the same, these slots receiving pins h h', projecting from a slide D, which is guided in the casing d and is acted upon by a spring e, tending to depress it. The lower end of the slide, however, rests upon a rod i, and this in turn is supported by one arm of a lever F, hung within a box F' at the lower corner of the sash, the other arm of this lever being acted upon by a rod i', which is guided horizontally in the lower portion of the sash and is acted upon by a lever G, hung within a box G', let into the face of the sash, this

lever G being acted upon by a spring j and by a lever H, also hung within the box G'. Precisely the same mechanism is employed 55 for each side of the sash, the two levers H being connected by a bridge-piece J, which is normally held in an elevated position by the action of the springs j upon the levers G; the spring e at each side of the sash consequently 60 depressing the slide D, and thus causing the pins h h' of said slide to so act upon the inclined slots in the locking-bolt f as to thrust the same outward into a recess of the retaining bar or plate b on the side bar of the frame. 65 When the sash is closed, the locking-bolts engage with the lowermost recesses of the bars b, and hence lock the sash firmly in the closed position; but upon depressing the bridge-bar J the slides D will, through the medium of 70 the levers and rods which we have described, be caused to rise, and their pins h h' will act upon the locking-bolts f, so as to withdraw the same from engagement with the recessed retaining-bars, and the sash can then be raised 75 to any desired extent, the locking-bolts being projected as soon as pressure is removed from the bridge-bar J, so that said bolts may be caused to engage with any desired recesses of the retaining-bars, and thus hold the sash 80 firmly in the desired position, effectually preventing either the rise or fall of the sash or the rattling of the same in the frame.

Although we prefer to provide each locking-bolt f with two inclined slots, each receiving 85 an operating-pin on the slide, but one slot need be used, if desired, and a single lever connected to the bridge-piece J and acting on the bolt f may replace the two levers G and H in some cases. For instance, the lever H 90 only may be used, the construction shown, however, being preferred.

When it is desired to lock the mechanism, so as to prevent tampering with it, a lever x, to be operated by a suitable key, may be used, 95 this lever having bolts x', which enter openings in the levers H of the operating mechanism, so as to lock the same in position, as shown in Fig. 1.

In order to lock two sashes together, the top of the lower sash is provided with a casing M, in which is suitably guided a spring-bolt N, adapted to engage with any one of a number of openings in a plate N' on the face

of the upper sash, this bolt being acted upon by a lever P, which is under control of the wedge-shaped upper end of the bar or slide D, which controls the bolt f, so that when the 5 slide is raised the bolt N will be withdrawn and the sashes unlocked, as will be readily understood on reference to Figs. 5 and 6. The box or frame d is cut away at the top, as shown in Figs. 3 and 4, so as to permit the 10 slide D to extend up to the top of the sash and act on the lever P in the manner set forth.

Having thus described our invention, we claim and desire to secure by Letters Patent—

1. The combination of a window-frame having 15 recessed retaining-bars at opposite sides, with the sash having at each side a pivoted and slotted locking-bolt for engaging with said retainer, a slide having pins adapted to the slotted portion of the bolt, so as to move 20 the same positively in both directions, and means for operating said slide, substantially as specified.

2. The combination of the frame of the window and its recessed retaining-bars, the sash 25 having pivoted and slotted locking-bolts for engaging with said retaining-bars, slides having pins adapted to the slots of the bolts, so as to move the same positively in both directions, horizontal rods guided on the sash near 30 the bottom of the same, pivoted levers interposed between said rods and the bolt-operating-slides, and means for moving said rods longitudinally, substantially as specified.

3. The combination of the frame and its recessed retaining-plates, the sash and its locking-bolts, the operating-slides for the latter, vertical and horizontal rods guided in the sash, levers interposed between said rods at the lower corners of the sash, and operating devices for the horizontal rods, comprising 35 opposite pairs of levers engaging with each other, one of said levers acting upon a horizontal rod and the other being connected by a bridge-piece to the opposite lever, substantially as specified. 40

4. The combination of the sashes, the spring-bolt carried by the lower sash and engaging with openings in the upper sash, a slide actuating said bolt, and operating devices for the slide carried by said lower sash, substantially as specified. 45

5. The combination of the frame and its recessed locking-bars, the upper sash having locking-openings, bolts carried by the lower sash and engaging with the upper sash and 50 with the locking-bar of the frame, slides for actuating said bolts, and means for operating said slides, substantially as specified. 55

In testimony whereof we have signed our names to this specification in the presence of 60 two subscribing witnesses.

FRANK FOWLER.
AMOS M. ULMER.
